UNITED STATES PATENT OFFICE

2,511,209

KEYLESS CUTOFF BOX

Ralph Bryan Johnson, Houston, Tex.

Application September 14, 1944, Serial No. 554,043

1 Claim. (Cl. 137—13)

1

The invention relates to a cut-off box for valves carried by buried pipes, such for instance as in water and gas piping to residential and industrial users.

It has been a practice heretofore to provide a cut-off box for the buried valves where it is necessary to have a key, which is inserted into the box and an attempt is then made to find the valve in order to effect the operation of cutting off or turning on the valve. In many instances the cover of the box has been removed or displaced. The box is either full or partially filled with earth or refuse and considerable difficulty is encountered in cleaning out the box, finding the valve, and attempting to fit the key thereto. In other instances, the box may have tilted or dislodged or moved out of alignment and it is difficult to locate the valve.

The present invention contemplates a structure which will be firmly anchored with respect to the pipe and with respect to the earth and which will be closed and have a key as a portion thereof so that the valve may be actuated by a handle at the surface and the inconveniences and disadvantages set out eliminated.

It is therefore one of the objects of the invention to provide a keyless cut-off box which will be anchored to the pipe.

Another object of the invention is to provide cut-off box having anchored plates which are adjustable relative to the box to accommodate its use in combination with buried pipes at different elevations.

Still another object of the invention is to provide a cut-off box which is closed and has an operating handle at the surface.

Still another object of the invention is to provide a cut-off box which can be fitted to pipes at different elevations so as to anchor the box and the cut-off handle in a rigid and permanent position.

Other and further objects of the invention will be readily apparent when the following description is considered in connection with the accompanying drawing wherein:

Fig. 1 is a vertical section view through the cut-off box with the section taken along the plane of the pipe.

Fig. 2 is a top plan view looking down on the cut-off box.

Fig. 3 is a sectional view taken on the line 3—3 of Fig. 1 and illustrates the same arrangement of the structure.

Fig. 4 is a section taken on the line 4—4 of Fig. 55

2

1 to illustrate the manner of the connection to the valve.

Fig. 5 is an end view of the arrangement of Fig. 1 and illustrates the manner of connection to a pipe which is buried a greater distance than the length of the box.

Fig. 6 shows the box as applied to a pipe which is near the surface.

In Fig. 1, the pipe 2 carries a valve 3 having a plug 4 which is to be turned in the opening or closing to control the flow of fluid through the pipe. The pipe of this sort is usually buried a distance below the surface of the earth and the valve 3 is usually located some distance from the residence or buildings to which the pipe extends and may be near the street or the alley in residential locations or in the basement in industrial buildings. The cut-off box is illustrated generally at 5 and embodies a hollow member 6 which may be cylindrical, rectangular or of any suitable configuration such as the square 7, having the rounded corners 8 as seen in Fig. 3.

This hollow body 6 is provided with slotted areas 10 on each side thereof which extends a substantial distance up into the body as indicated by the dotted lines 11 in Fig. 6.

The top of the hollow body is open and it is arranged for placement in the earth so that the cap 15 thereof is positioned substantially at the surface 16 of the earth as seen in Fig. 5.

If the pipe 2 is buried to a relatively shallow depth, the body 6 may project below the pipe as seen in Fig. 6 where the pipe 2 passes through the slot 10 on opposite sides of the housing. Such an arrangement would provide a cut-off box about the valve, but it has been found desirable to firmly anchor the box with respect to the pipe and to accomplish this, a plate such as 20 has been positioned on opposite sides of the box 6. Each of these plates has a plurality of openings 21 therein which are arranged to embrace the pipe and are preferably the size to fit about the pipe. These plates also have a plurality of openings 22 therein arranged to receive the screws or bolts 23 so that the plate can be suitably fastened to the box or housing. With this construction the box is firmly anchored in position and fixed relative to the pipe so that it cannot become dislodged with respect to the valve 3.

To facilitate this anchoring, each of the plates 20 has an inwardly extending rib 25 as best seen in Fig. 3 and the openings 21 pass through this rib and the rib is of a width to fit in the slots 10. This eliminates any tilting or tipping action of the box relative to the pipe or the anchor plates

3

and insures a rigid construction. Fig. 1 and Fig. 5 show the arrangement where the pipe 2 is buried a greater distance in the earth than is illustrated in Fig. 6. In fact, the pipe of Figs. 1 and 5 is below the lower end 30 of the box so that the pipe passes through the plates but not the box.

It seems obvious that the plates may be of any desired length, depending upon the depth of the pipe or valve which is to be housed and that the plates are adjustable by moving the screws or bolts 23 to the desired openings.

In order to manipulate the valve 3, the spindle 40 has been shown which is preferably non-circular and fits into a nipple 41, having a slot 42 therein to fit over the wing 43 of the valve 3. This coupling 41 can then be affixed to the wing 43 by means of a wire 44 so that it is suitably anchored. The upper end of the spindle 40 passes through a bushing 46 rotatable in the hub 47 of the cap 15. The cross pins 48 serve to hold this hub or head 46 into position against vertical movement and the hub also carries an extension or handle 49 by which the spindle 40 may be rotated in turning the valve off or on. Fig. 2 shows the stop member 50 arranged to be engaged by the lug 51 on the handle 49 to limit the turning action in moving the valve to opening position; whereas, a similar stop 53 serves to limit the valve in its closed position.

Fig. 6 shows that the lug and the stops 50 and 53 each have a suitable opening 54 therein so that a lock 55 may be applied in locking the handle in either open or closed position. These stops are important because of the force which might be applied to the handle 49. Such a force could

4

5 very easily shear the stop pin 55 of the valve 3 and permit the valve to be turned through another half turn. The drain vent 56 would then be opened through the valve plug to the pressure side of the valve and result in leakage.

10 Broadly, the invention contemplates a cut-off box which adapts itself for position in the earth to protect a valve or a buried pipe line and which is adjustable to accommodate the valve at various depths and under varying circumstances.

15 What is claimed is:

A cut off box comprising a housing, a cap therefor, a handle having a hub rotatably mounted in said cap, a valve stem mounted in said hub, and 20 adjustable anchor and support means for said housing comprising a pair of spaced plates having a plurality of longitudinally spaced pipe receiving openings therein, and means to connect said housing to said plates.

25 RALPH BRYAN JOHNSON.
